(57) **CLAIM**

The ornamental design for a slide clamp as shown and described.

DESCRIPTION

FIG. 1 is a front, top and right-side perspective view of a first embodiment of a slide clamp,

FIG. 2 is a front elevation view thereof;

FIG. 3 is a back elevational view thereof;

FIG. 4 is a right-side elevational view thereof;

FIG. 5 is a left-side elevational view thereof;

FIG. 6 is a top plan view thereof;

FIG. 7 is a bottom plan view thereof;

FIG. 8 is a front, top and right-side perspective view of a second embodiment of a slide clamp,

FIG. 9 is a front elevation view thereof;

FIG. 10 is a back elevational view thereof;

FIG. 11 is a right-side elevational view thereof;

FIG. 12 is a left-side elevational view thereof;

FIG. 13 is a top plan view thereof; and,

FIG. 14 is a bottom plan view thereof.

The ornamental design which is claimed is shown in solid lines in the drawings.

The broken lines show portions of the slide clamp that form no part of the claimed design.
